UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

MACHINE FOR PRESENTING LIQUID OR VISCOS MATERIAL.

1,145,412.

Specification of Letters Patent.

Patented July 6, 1915.

Continuation of application Serial No. 490,927, filed April 19, 1909. This application filed March 25, 1910.
Serial No. 551,556.

To all whom it may concern:

Be it known that I, FREDERICK M. FURBER, a citizen of the United States, residing at Revere, in the county of Suffolk and

5 State of Massachusetts, have invented certain Improvements in Machines for Presenting Liquid or Viscous Material, of which the following description, in connection with the accompanying drawings, is a specification,
10 like reference characters on the drawings indicating like parts in the several figures.

This invention relates to machines for presenting liquid or viscous material in position to be applied to stock and is herein shown as embodied in a machine designed for presenting shellac or similar material in position to be applied to such stock as toe stiffening material of a shoe upper. This stiffening material comprises superposed layers of fabric or leather, the adjacent faces of which are to be coated with shellac which is absorbed more or less by the fabric or leather and when it dries sticks the layers together and stiffens them so that they retain the shape of the last or form over which they have been laid to dry. The shellacking operation is usually performed in connection with the assembling, pulling-over, and lasting operations which follow one another at short intervals so that the shellacked fabrics forming part of the shoe upper materials are incorporated in the lasted shoe before the shellac has time to dry or set and thus the toe stiffener takes 30 the shape of the toe portion of the last. Liquid shellac evaporates rapidly so that it is necessary to avoid exposure of the shellac to the air as much as practicable.

With these conditions in view the present 40 invention has for its object to provide an apparatus by which a charge containing a proper quantity of shellac for coating one shoe stiffener can be withdrawn from a reservoir and presented in a suitably distributed or spread out condition to permit it to be readily applied to the surface which is to be coated.

An important feature of the invention 50 consists in providing a presenter suitably formed and arranged to be moved into a

reservoir of shellac and withdrawn carrying a substantially uniform charge of shellac properly distributed over its surface so that when the stock to be stiffened is laid against the surface of the presenter it will be coated 55 to a predetermined extent.

Other features of this invention include novel means for actuating the presenter and a novel arrangement for maintaining a substantially uniform level of shellac in the 60 reservoir.

These features and such others as may appear in the following description of the apparatus, including certain combinations of parts and more important details of construction, will be definitely pointed out in the claims at the end of the description.

Referring now to the accompanying drawings:—Figure 1 is a perspective of the machine with the presenter in the reservoir. 70 Fig. 2 is a perspective of the machine with the presenter withdrawn from the reservoir. In this figure certain parts of the machine which are shown in Fig. 1 have been omitted. Fig. 3 is a vertical cross-section 75 of the shellac reservoir and Fig. 4 is a perspective in detail of the divided driving shaft and the latch, the parts of said shaft being in position to cause said shaft to be rotated.

Referring now to the accompanying drawings, the machine comprises a standard 1 which carries a reservoir 3 having a storage compartment 5 and a loading compartment 7. This loading compartment is closed 85 except for a port 79 and a slot 9 in its top wall which is designed to receive a presenter 11, said presenter being shown in said compartment in Figs. 1 and 3 and in its delivery position in Fig. 2. This presenter is 90 a plate having substantially the contour of the portion of stock which is to be coated with shellac. The side faces of the presenter are provided with horizontal ribs spaced a substantial distance apart to form 95 horizontal grooves into which the shellac will enter when the presenter is submerged in the reservoir and from which the shellac will be absorbed by the stock pressed against the sides of the presenter.

2
 In the drawings, both sides of the presenter are ribbed, as described, in order to coat similarly the adjacent faces of two pieces of stock. If it is desired to coat only one surface of stock, one side only of the presenter will be formed as described for carrying shellac. The arrangement of horizontal ribs is of particular advantage in enabling the presenter to take up and carry in a uniformly distributed condition such fluid material as shellac which would flow freely out of mere pockets or depressions in a roughened surface. The ribs which are rectangular in cross section form dams extending entirely across the presenter and offering no opportunity for the shellac to flow downwardly at any special point.

The presenter is vertically adjustable on a support 15 to which it is fastened by a bolt 13. In order to cause the presenter 11 to be moved from loading to delivering position without being tilted the support or link 15 is pivoted at 17 and 19 to cranks 21 and 23. The crank 23 is fast to a shaft 25 rotatable in a bearing 29 which is shown as integral with the reservoir. A collar 27 is fixed upon the shaft 25, and a coiled spring 31 which has one end fast to the collar 27 and the other end fast to the bearing 29 tends to hold the crank 23 normally in the position shown in Fig. 1, a stop 33 on said crank being arranged to coöperate with a lug 35 to limit the motion of said crank. The crank 21 is fast to a divided shaft 37, the parts of which will be designated for convenience the power end and the crank end. This shaft is rotatably mounted in bearings 39 and 41 and has fast to it two collars 43 and 45 there being a coiled spring 47 located between the collar 45 and the bearing 39, said spring tending to cause relative longitudinal movement between the parts of said divided shaft 37. Fast to the extremity of the power end of the shaft 37 is a member 49 carrying a friction disk 51 which coöperates with a similar disk 53 fast to a driving pulley 55, said pulley being freely rotatable on the shaft 37 when the parts are in the position shown in Fig. 1 and being adapted to be clutched to said shaft when the disks 51 and 53 are pressed together.

Turning now to Fig. 4, it will be seen that the adjacent ends of the parts of the shaft 37 have flat faces which overlap so that while relative longitudinal movement between the parts is permitted, relative rotation is prevented. In order to limit the movement of the parts of the shaft toward each other, a stop 54 is provided on the crank end which coöperates with a shoulder formed on the power end. As has been stated, the spring 47 tends to separate the parts of the shaft and thereby to separate

the friction disks 51 and 53 so as to permit free rotation of the pulley 55. In order, however, to cause said pulley to be clutched to the shaft when desired, a latch 57 normally held as shown in Fig. 1 by a spring 58 is pivoted to the reservoir at 59 and a chain attached to its lower end passes over a roller 63 and is connected with any suitable treadle 64. When the treadle is depressed the collar 45 and with it the power end of the shaft is forced toward the crank end thereby clutching the pulley 55 to said shaft. Inasmuch, however, as only a partial rotation of the shaft is desired in order to bring the presenter into the position shown in Fig. 2 a notch 65 is formed in the collar 45 which, when the shaft has moved through 180° , arrives opposite the projection 67 upon the latch whereupon the spring 47 moves the power end of the shaft away from the crank end and thereby disengages the pulley 55. At the same time, the flat bottom face of the projection 67 engages the flat radial face of the notch 65 and prevents the shaft from being rotated in the opposite direction by the spring 31. The presenter is consequently held in the position shown in Fig. 2 so that the operator may wipe the shellac from its sides. In order to insure that the rotation of the shaft 37 shall cease at the end of 180° a stop 69 on the crank 21 is arranged to contact with a fixed lug 71. When the treadle is released the spring 58 pulls the latch to the position shown in Fig. 1 whereupon the shaft 25 under the influence of the spring 31 becomes a driving shaft and returns the presenter to the loading compartment of the reservoir as shown in Fig. 1.

With the construction thus far described, it might happen that when the cranks 21 and 23 reached dead center the link 15 might move angularly, that is, while the crank 21 went forward the crank 23 might go backward. In order to obviate the possibility of such a movement of the parts, a third crank 73 journaled on a stud 75 is pivoted to an extension of the link 15 at 77, the effect of this construction being to prevent any angular movement of the link 15 and to maintain the pivot 17 at all times vertically above the pivot 19, it being understood that the cranks 21, 23 and 73 are all of the same length.

Turning now to Fig. 3, a port 79 connects the compartment 5 of the reservoir with the loading compartment 7, a valve 81 mounted on a stem 83 being provided for controlling said port. The stem of the valve is threaded through a bore in the lower part of the reservoir so that by rotating said stem the port 79 may be opened or closed. An air passage 85 leads from the upper portion of the compartment 5 and terminates in a

branch 87, the mouth of which is adjacent the bore which receives the stem 83. A handhold 89 is pinned to the stem 83 and a washer 91 is placed on said stem between the 5 handhold and the wall of the reservoir. With this construction, when the handhold is rotated to open the port 79, the air passage is closed as shown in Fig. 3 and vice versa, when the port 79 is closed the air passage is 10 opened. Fastened to the top of the reservoir by bolts 93 and extending into the lower part of the reservoir is a filling tube 95 provided with a loosely fitting cover 97. With this reservoir the surface of the liquid in the 15 loading compartment will lie in a plane passing through the uppermost point of the port 79 irrespective of the level of the liquid in the storage compartment 5 provided the liquid in this compartment extends above 20 the port 79. When it is desired to replenish the supply, the handhold 89 is rotated to close the port 79 and open the air passage 85. The cap 97 is then removed and the shellac or other liquid is poured into the filling tube. 25 The advantages of this construction are that the opening in the top of the reservoir need not be air tight and that the reservoir may be filled at any time without interrupting the operation of the machine.

30 The operation of the machine is as follows: The treadle is depressed thereby rocking the latch on its pivot and bringing the friction disks 51 and 53 into contact. This causes the pulley 55 to be clutched to the 35 shaft 37 whereupon the crank 21 moves angularly until the notch 65 permits the friction disks 51 and 53 to be separated by the force of the spring 47. The mechanism is thus brought to the position shown in Fig. 2.

40 The operator then applies the material to the presenter and wipes off the shellac upon it after which he releases the treadle. The spring 58 then withdraws the latch from the notch 65, and the spring 31 causes the presenter to be moved back into the loading 45 compartment as shown in Fig. 1.

This application is a continuation so far as common subject-matter is concerned of application Serial No. 490,927.

50 Having described my invention what I claim as new and desire to secure by Letters Patent of the United States is:—

1. A machine of the class described having, in combination, a presenter having 55 freely accessible opposite faces to which the material to be coated may be manually applied, and means for actuating the presenter into and out of delivering position, and automatic means for causing a pause in the 60 movement of the presenter when it reaches delivering position.

2. A machine of the class described having, in combination, a reservoir, a presenter having freely accessible opposite faces to

which the parts of a shoe tip may be applied 65 manually and means for withdrawing said presenter from said reservoir and for automatically bringing it to rest alternately in receiving and delivering positions.

3. A machine of the class described having, in combination, a reservoir, a presenter having freely accessible opposite faces to which the material to be coated may be manually applied, and treadle-controlled operating means for moving the presenter from 75 loading to delivering position when the treadle is depressed and from delivering to loading position when the treadle is released.

4. A machine of the class described having, in combination, a reservoir, a presenter having freely accessible opposite faces to which the material to be coated may be manually applied, a treadle, means becoming operative upon actuation of said treadle for 80 withdrawing said presenter from said reservoir, and means becoming operative upon release of said treadle for returning said presenter to said reservoir.

5. A machine of the class described having, in combination, a reservoir, a presenter, a support therefor, a crank arm pivoted to said support, a treadle, and means controlled by said treadle for causing said crank to move angularly a predetermined distance. 90

6. A machine of the class described having, in combination, a reservoir, a presenter, a support therefor, a crank arm pivoted to said support, a treadle, means controlled by said treadle for causing said crank to move 100 angularly a predetermined distance, and means becoming effective upon release of said treadle for reversing the motion of said crank.

7. A machine of the class described having, in combination, a reservoir for an adhesive substance, a presenter having substantially vertical operative faces to which the material to be coated may be manually applied and adapted to carry a thin coating of 110 said substance, said presenter being movable from said reservoir into a delivering position readily accessible to the operator, means for so moving said presenter and means for holding said presenter for a desired period 115 in its delivering position.

8. A machine of the class described having, in combination, a reservoir for an adhesive substance, a presenter having a substantially vertical operative face of extended area adapted to carry a thin coating of 120 said substance, automatic means for causing said presenter to remain normally in said reservoir, means for withdrawing said presenter, and automatic means for arresting 125 the movement of the presenter at and for holding it in a predetermined position.

9. A machine of the class described hav-

ing, in combination, a presenter in the form of a plate whose opposite faces are freely accessible to permit the manual application of shoe tip stock thereto and are adapted to 5 carry an adhesive material, a reservoir for said material into which said presenter normally dips, and means for moving said presenter to and for bringing it to rest in a position spaced from said reservoir and in 10 proximity to said operator to permit a piece of toe tip stock to be wiped across the side of said presenter.

10. A machine of the class described having, in combination, a presenter in the form 15 of a plate having an outline to correspond approximately to that of the toe tip stock, a reservoir for adhesive material provided with a slot through which the presenter may be moved into said reservoir, and means for 20 moving said presenter from a position in said reservoir to a position spaced from said reservoir in proximity to the operator to permit the flaps of the toe tip stock to be slipped over said presenter and drawn down 25 the sides thereof to remove adhesive material therefrom.

11. A machine of the class described having, in combination, a reservoir, a presenter, a support therefor, two cranks having their 30 axes of rotation in approximately the same vertical plane, a third crank of the same length as the other two, pivots connecting said cranks with said support and means for rotating one of said cranks through a predetermined arc.

12. A machine of the class described having, in combination, a reservoir, a presenter having freely accessible faces to which the material to be coated may be manually applied, power actuated mechanism for moving 40 said presenter to a position accessible to the operator, means for holding the presenter in such position for a desired time, and resilient means for returning said presenter to said reservoir.

13. A machine of the class described having, in combination, a reservoir, a presenter, power actuated mechanism for moving said presenter to delivering position, said mechanism including a clutch, a rockshaft and a 50 starting and stopping device for causing said clutch to be operative during a partial revolution, a treadle for actuating said starting and stopping device, and resilient means for returning said rockshaft to its initial 55 position.

14. A machine of the class described having, in combination, a presenter, means for moving said presenter from loading to delivering position and a reservoir comprising 60 a loading compartment to receive the presenter, a storage compartment, a port connecting said compartments, an air passage

leading from said storage compartment, and means for closing and opening said port and 65 passage alternately whereby said storage compartment may be filled without interrupting the operation of the machine.

15. A machine of the class described having, in combination, a presenter, means for 70 moving said presenter from loading to delivering position and vice versa, and a reservoir comprising a loading compartment, a storage compartment, a port connecting said compartments, an air passage leading to the 75 upper portion of said storage compartment, a filling tube extending into said storage compartment and means for alternately closing said port and opening said air passage.

16. A machine for delivering shellac or 80 the like to toe tip stock having in combination a reservoir, a presenter comprising a thin plate having a contour which corresponds substantially to that of the toe tip stock and adapted to be loaded with the 85 shellac and then moved into position to permit the toe tip stock to be wiped across the face of the presenter, and means for actuating said presenter.

17. A machine of the class described having, in combination, a reservoir for stiffening material, said reservoir being provided with an opening in the form of a slot, a presenter having freely accessible opposite faces to which the material to be coated may be 95 manually applied and adapted to move in a fixed path from one extreme position in said reservoir through said slot to another extreme position readily accessible to the operator, and means controlled by said operator for moving said presenter to and holding 100 it in either position.

18. A machine of the class described having, in combination, a reservoir for stiffening material, said reservoir being provided 105 with an opening in the form of a slot, a presenter adapted to move in a fixed path from one extreme position in said reservoir through said slot to another extreme position readily accessible to the operator, said 110 presenter being provided with ribs whereby the stiffening material is prevented from being wiped off from the body of the presenter by the walls of the slot, and means controlled by the operator for moving said 115 presenter to and holding it in either position.

19. A machine of the class described having, in combination, a reservoir for a stiffening substance closed except for a slot in its 120 upper portion, a substantially flat presenter having a carrying face that is freely accessible to manual application of the parts to be coated, said presenter being normally located within said reservoir in position to be 125 loaded with stiffening substance, and means

controllable at will for moving said presenter to and holding it in a position readily accessible to the operator, there being a free and unobstructed space beneath said presenter in said position whereby the operator may wipe off upon a piece of stock the stiffening substance carried by said presenter.

Copies of this patent may be obtained for five cents each, by addressing the "Commissioner of Patents, Washington, D. C."

In testimony whereof I have signed my name to this specification in the presence of two subscribing witnesses.
